PRINTING MACHINE

Emmett C. Hartley, Cleveland, Ohio, assignor, by
mesne assignments, to Addressograph-Multi-
graph Corporation, Cleveland, Ohio, a corpora-
tion of Delaware

Application August 12, 1935, Serial No. 35,707

42 Claims. (Cl. 101—58)

This invention relates primarily to the provision of a method and apparatus for determining operative identity of related elements, such as sets of control members and corresponding printing devices, separately arranged in a predetermined order and fed in step with each other, say in separate mechanisms, or in the same mechanism, for effecting a signal or like operation, as, for illustration, stopping of the feeding means 5 for such members and/or devices, if for any reason one of the members or devices is, for example, out of position in or missing from its respective set.

The general object of the invention is to provide an improved method and apparatus to identify individual elements of one set of devices with individual elements of another set, supposed or intended to correspond therewith, and particularly to effect such identification during a useful 10 operation on or in connection with the elements of one set by appropriate mechanism.

More specifically, the invention contemplates the provision of an identification system and apparatus between individual printing devices (such as address printing devices) which are supposedly arranged or stacked in a predetermined order and fed one by one to a printing position, and, corresponding index or control members (such as perforated tabulating machine control cards) 15 which are also supposedly arranged or stacked in the same predetermined order as the printing devices. Generally, the control members individually relate to the same or correlated subject matter as the corresponding printing devices, and operate in connection with such printing devices to produce a unitary or unified result, the ultimate purpose being to make certain that both the printing devices and the index or control members mutually agree with each other or are in 20 the proper order in respective sets of devices and members.

A specific example of the problem involved and the solution thereof is as follows: Perforated cards are made up for say the entire customer 25 list of a commercial organization to control a tabulating machine. These are kept in a certain order in groups. Address printing devices with index tabs thereon are made up to represent the same list and similarly ordered and 30 grouped.

The cards are generally utilized to control a tabulating machine and cause it to print, on invoices, the number of units and the money value thereof chargeable to the consumer or customer 35 represented by the individual card. Each card is

provided with suitable indicia to cause such operations to take place automatically consequent upon the feeding of the card through the tabulating machine. The card is likewise provided with indicia to represent the customer or consumer. Generally this latter represents or comprises the account number.

The customer's or consumer's name and address is also printed on the invoice. This, however, is usually done after the amounts have been 40 printed, and with a different mechanism. It may, however, readily be done either before or during the printing of the amounts by the tabulating machine. In many instances, however, it is highly advantageous to utilize for this purpose 45 a printing machine of the type generally known as an addressing machine. Such machines usually utilize a series of individual printing devices bearing thereon a printing member carrying printing characters. The printing characters of 50 each printing device are so arranged that, consequent upon the passing of such device through the addressing machine, the name and address of the customer or consumer represented by that printing device will be impressed on the work.

Since the amounts are printed by one mechanism and one set of control members, and the names and addresses are printed by a different mechanism and a different set of control members (i. e. address printing members), it is possible, without the use of the present invention, that, due to a probable loss of one member in either group or a disarrangement of one member in a group, an entire group of invoices may be erroneously printed. For instance, if the first address plate in a group is missing and the invoices fed to the addressing machine in the same order as they were discharged from the tabulating machine, each invoice will bear the name and address of the customer or consumer whose name 55 and address should be on the succeeding invoice.

However, when the printing devices of each group are fed step by step to a printing mechanism, such as an addressing machine, and the control cards of the corresponding group, which are supposed to be arranged in the same order as the address printing plates, are fed step by step in another mechanism, it is possible, utilizing the present invention, to prevent errors due to the disarrangement of either a control card or 60 printing device.

The illustrated embodiment of the present invention detects, in connection with the feeding of each printing device or card, whether or not the device or card is in proper order, that is,

whether or not the device being fed corresponds to the card being fed. If the card and device do not correspond, that is detected, and a signal or a stopping of the operation of both the printing device and card feeding mechanisms is effected, so that appropriate investigation or correction may be made. When this comparing operation is effected, immediately after or before the operation on the invoices by the tabulating machine, there is for all practical purposes, no opportunity for the displacement or disarrangement of the cards, invoices or address plates during the transfer from one mechanism to another. Such disarrangements, displacements or losses may, however, frequently occur in the interim between invoice or tabulating periods.

In many commercial organizations, the control cards for the tabulating machine or tabulating mechanism may comprise a series of cards for each customer or consumer, including a master or control card and one or more other cards. It is obvious that there need be but one address printing member for each customer. It is therefore an object of the present invention to so provide a method and apparatus, whereby the cards may be fed step by step and only one address printing member advanced or fed for each series of cards, regardless of the number of cards in the series, and without interruption of the card feed.

When a series of cards are used, they often represent different classes of service, such as electric power, water, gas, steam, etc. These cards may be called service cards, and there is usually one service card for each class of service. The service cards are always associated with a control or master card when stacked. It is an object of the present invention to provide a method of checking the service cards, as well as the control or master cards. This is accomplished by providing the service cards with indicia to represent the account number, as is done with the control cards, and checking or comparing the service cards with the address printing device while restraining the feeding of the device until all of the cards of the series have been fed and checked.

Now it sometimes happens that a customer will have service throughout the year except during a certain billing period, during which period the customer will have no service whatsoever, and hence will require no bill. In such instances the service and control cards will lack indicia to cause the printing of amounts on the invoice by the tabulating machine, and hence no bill will be fed to the address printing machine for that account. The present invention contemplates the provision of a method and apparatus which will detect the corresponding printing device, compare it with the service and control cards corresponding to that account and pass the address printing device through the addressing machine without making an impression therefrom, or without feeding an invoice through the addressing mechanism. This, therefore, is another object of the present invention.

It is a further object of the invention to provide a method and apparatus utilizing a set of cards wherein each card in the set will be identified or in effect compared with the other cards of the series. This is accomplished by comparing each card of the set with the same printing member.

Another object is to provide an identification by means of which a set of devices, each pair of which are cross-indexed and numerically identi-

fied by the use of a lesser number of index positions than are actually represented in the numerical system used.

Other objects of the invention relate to the selecting of which of the printing devices are to be printed or are to be skipped, as the case may be, and provides for printing in duplicate without disturbing the order of either the printing device or the cards.

The invention is also concerned with the provision of an efficient electrical arrangement for carrying out the above and related purposes.

Other objects of the invention will become more apparent from the following description, reference being had to the accompanying drawings, in which a preferred form of mechanism is illustrated for carrying out my improved method. The essential novel features of the invention will be more fully set forth or summarized in the claims.

In the drawings, Fig. 1 is a plan view illustrating an addressing mechanism, together with certain mechanism which cooperates with the address printing devices to effect their identification or comparison with control members or cards; Fig. 2 is a transverse vertical section through the addressing mechanism and certain paper feeding mechanism therefor, the plane of the section being indicated by the line 2—2 on Fig. 1; Fig. 3 is a centrally located longitudinal vertical section through the mechanism illustrated in Fig. 1, as indicated by the lines 3—3 on Fig. 1; Figs. 4, 5, and 6 are sectional details, as indicated by the correspondingly numbered lines on Fig. 1; Fig. 7 is a sectional detail on a scale somewhat larger than that shown on Fig. 1, the plane of the section being indicated by the line 7—7 in Fig. 1; Fig. 8 is a transverse vertical section, on the same scale as Fig. 7, the plane of the section being indicated by the correspondingly numbered lines on Fig. 1; Fig. 9 is a transverse vertical section, on a scale somewhat larger than that shown on Figs. 7 and 8, the plane of the section being indicated by the lines 9—9 on Fig. 1; Fig. 10 is a sectional detail, as indicated by the correspondingly numbered lines on Fig. 9; Fig. 11 is a plan view of a card-feeding mechanism, certain of the parts being broken away to more clearly illustrate the internal construction of the mechanism; Fig. 12 is a vertical section, as indicated by the line 12—12 on Fig. 11; Fig. 13 is a plan view of one form of address printing device, for which the printing mechanism illustrated is especially adapted; Figs. 14 and 15 are perspective views of different index tabs adapted for use with the printing device for identification purposes; Fig. 16 is an electrical diagram of electrical circuits utilized in effecting the various operations of the mechanism; Fig. 17 is a detailed diagram of certain of the electrical circuits; Figs. 18 to 28 are fragmentary electrical diagrams illustrating various proving or comparing circuits set up by different combinations of index tabs and perforations of the address printing devices and cards, and illustrates under which conditions the circuits will be operated to cause the machine to proceed in the usual manner, and which circuits are operated to stop the mechanism so that the operator may readjust or restore the cards or devices to their proper corresponding positions; Fig. 29 is a diagram illustrating the different settings of the index tabs to represent the numerals zero to 9; Fig. 30 is a diagram illustrating the timing of the various mechanisms utilized in the apparatus illustrated in the drawings.

The invention has been illustrated with two separate mechanisms which are in some respects only partially shown. These two mechanisms, however, are interconnected by suitable electrical mechanisms or conduits and comprise a complete machine, all of the cooperating parts of which are illustrated. As shown in the drawings, such mechanisms are generally indicated and represented as A and B, A representing the address printing mechanism, including the feeding mechanism for the address printing devices, while B generally indicates the control card feed mechanism. If desired, the mechanism B may be considered part of a tabulating machine unit, wherein in the control cards C (Figs. 11 and 12) are provided with perforations in certain definite locations thereon, to control the functions of suitable tabulating mechanism, or other devices not shown but by means of which various data are arranged on printed mail matter, as, for instance, on bills or invoices, to consumers of power companies or commercial organizations. However, such mechanism may be, as shown, simply a card-feeding mechanism, incorporated as a part of the addressing machine, or as shown, as a separate unit therefrom.

The mechanism A represents an address printing machine, wherein the address printing devices D are stacked or arranged in a supposedly predetermined order in a suitable magazine; withdrawn from such magazine and fed one by one to various positions, including an identifying position, a selection position, and a printing position; printed from; and finally reassembled in the same order in another magazine.

The two mechanisms are correlated by the present illustrated embodiment of the invention, so that each control card corresponding to a given printing device is first identified with the specific printing device, at respective stations F¹ and F in the units in which they are fed. While the units are in such identifying position, should they fail to identify or correspond, that is, represent the same account, the whole machine will be stopped automatically and will remain stopped until appropriate correction is made, otherwise the mechanism continues to function in repeating cycles.

After identification, both the card and printing device are fed to a second position G¹ and G in their respective feeding mechanisms, in which positions the arrangement of the indicia on the card will determine whether or not an imprint is to be made from the corresponding printing device.

In the second position G¹ and G, just mentioned, the printing device alone may operate to set the addressing machine for a printing or non-printing operation, as desired. At the position H of the printing device, printing is effected or skipped according to a prearranged setting, as will be later described. While I have shown a second position E of the address printing plate, this position is only incidental to the specific construction of the address printing mechanism illustrated.

The control card C, as shown in Figs. 11 and 12, is of the type commonly known as a "Powers" double position card. This card has on one face a plurality of similarly spaced vertical columns of numerals or symbols, 0, $\frac{1}{2}$, $\frac{3}{4}$, etc. in tabulated form. Only portions of the entire area and indicia thereon are used for the present purpose, the remaining portions of the card ordinarily contain symbols or indicia such as perforations

for controlling the operation of a tabulating machine or other similar mechanism.

Assuming the upper left-hand portion of the card, namely, the portion K, is known to be used for identification, this, it is noted, is provided with vertical columns of numerical symbols comprising odd numbers running from one to nine, and closely adjacent thereto and diagonally therebelow, a "column" of even numbers, 2 to 8, followed by the conventional symbol of addition (+) thus forming pairs of numerals or symbols, $\frac{1}{2}$, $\frac{3}{4}$, etc. to $9/+$. This vertical row of pairs of symbols will hereinafter be considered and referred to as a single column. Each pair of symbols represents a possible punch or perforation location.

The perforations made by the punch are indicative of one or the other of the numerals or symbols of the pair punched out in a given column. Perforations in the first column from the left to right represent thousands, the next column hundreds, the next column tens, and the next column units, these being sufficient, even in the case of larger numerals, to identify. The last three digits of the larger numerals being sufficient for practical purposes, no higher number than one is contemplated to be used in the thousands column, although obviously higher numbers could be readily used.

Since the perforation is always made in the same position with respect to a pair of symbols, such perforation cannot of itself definitely represent either symbol punched. Wherefore, an additional perforation is made on the card to indicate which of the symbols punched controls. For instance, where a pair of symbols, say $\frac{1}{2}$ is punched, and there is an additional punch in the $9/+$ position, the even number of the punched pair is the controlling symbol. Whereas, when only the position $\frac{1}{2}$ is punched, the odd number of the pair is the controlling symbol. To represent the number 9, the 9 position only is punched, the same as for any other odd number. Zero is indicated for each column above the $\frac{1}{2}$ position and a perforation in this position alone represents zero. The above described specific arrangement of symbols is arbitrary and may be greatly modified. The invention will, however, be explained in connection with this arrangement.

The perforation location shown at M, as well as the two double columns of symbols at J, are locations for special perforations (printing identification perforations to be later described) and it will be well to remember that the perforations in the zone J neither relate to nor are essential to the portion of the system or method hereof by which the printing devices and cards are identified or compared for operative identity.

The perforations in the zone or area K of the card cause the energization of individual electrical circuits, one for each punch position, either by means of brushes or contact plates or plungers, making a possible electrical circuit through the perforations when present or by any other appropriate means. Each combination of perforation locations sets up a different electrical circuit, which is, in a measure, independent of the circuit made by other combinations, as will be later shown in connection with the electrical diagrams of Figs. 18 to 28.

Each address printing device D comprises, as shown in Fig. 13, a metallic holder d arranged to removably support a printing member, such as the address printing plate d1. The holder also carries, as shown at d2, an identification slip on

which data may be carried for visible identification. The printing devices are individually characterized in accordance with identifying punchings of the corresponding card C. This characterization may be by a similar system, that is, by use of perforations. However, as shown, I prefer to utilize tabs T which may be removably inserted in suitable tab-retaining pockets of the printing device. Two of such tabs are illustrated in perspective in Figs. 14 and 15 respectively.

As shown, in Fig. 14, the tab comprises a tongue "t1" arranged to coact with the retaining pocket of the printing device holder, and extend outwardly, the portion "t" arranged to project beyond the margin of the printing device so as to coact with suitable selector members, such as electrical switch members, hereinafter to be more fully described. As shown, the tab of Fig. 14, which will be referred to as a split printing tab, has a selector area "t2". It will be noted that such area is substantially half of that of a whole tab, indicated by the dotted lines in Fig. 14. By reversing this split tab when placing it on the printing device two effective tab positions are obtained for each tab-retaining pocket of the printing device. Fig. 15 illustrates a different type of tab. As shown, this tab is provided with an embossed area t3 which is raised above the normal plane of the tab and serves a purpose hereinafter to be described.

In the embodiment illustrated, three tab retaining pockets are assigned to each of the units, tens, and hundreds group or "column", and one pocket to the thousands column. By so assigning three pockets to each column (except thousands) six effective tab positions are provided for each group of three, and these, as shown in Fig. 29, represent 0, 1, 3, 5, 7, and 9, respectively. To represent 2, 4, 6, and 8 the printing device is tabbed as for 1, 3, 5, and 7, and an additional tab is provided, namely, the embossed tab of Fig. 15, in the "9" position tab pocket. In the case of representing the numeral 8, a special full tab is used, the right hand portion of which is embossed (example shown in Fig. 23). Since only "zero" and "one" are required in the thousands column, only one tab pocket is required for such column.

A card perforated to indicate the number "0594" is shown at the right in Fig. 11. In viewing the card, this sheet of drawings may now be turned vertically. The left hand column is the thousands column and is perforated in the zero position. The next column or hundreds column has a perforation in the $\frac{5}{6}$ position. This, as heretofore explained, designates a 5. The next or tens column has a perforation in the $9/+$ position which designates a 9; and the units column has a perforation in both the $\frac{3}{4}$ and the $9/+$ positions, both of which are required to represent a 4.

An address printing device tabbed to represent the same number, namely "0594" is shown in Fig. 13. The tab pocket in the thousands column is occupied by a left-hand split tab, the middle pocket of the hundreds group or column is occupied by a right-hand split tab, the right-hand pocket of the tens group is occupied by a right-hand split tab, and the middle and right-hand pockets of the units group are occupied by a left-hand split tab and a plain embossed tab respectively. This arrangement of tabs represents the number "0594". The method and apparatus of the present invention compares a printing device,

such as above described, with a card, such as above described.

Before describing the various electrical circuits which are energized to control the card and printing device feeding mechanisms, the addressing machine or printing mechanisms will be described.

The mechanism "A" or the address printing mechanism will now be described. This mechanism is best illustrated in Figs. 1 to 10, inclusive, and comprises a driving mechanism, a printing device feed mechanism, a printing mechanism, an electric selector mechanism, a mechanical selector mechanism, an identification mechanism, a sheet feed mechanism, and a web feed mechanism, the latter two mechanisms being used selectively depending on the type of material (sheets or webs) being printed upon.

Driving mechanism

The various mechanisms are all operated under the control of electric circuits hereinafter to be described and from a common source of power such as an electric motor (not shown) which is drivingly connected to a pulley 20, rotatably mounted on a shaft 21 which is journaled in suitable bearings in the machine frame 30. The pulley 20 is drivingly connectible with the shaft 21 by a suitable clutch. Such clutch is shown in Figs. 1 and 4, and as there shown the clutch comprises a latch 22 pivoted to the pulley 20 and normally drawn into engagement with a shaft member by a spring 23. This clutch may be manually operated by a shipper lever 24, which rocks a slotted cam 25 (Fig. 4) having a pin and slot connection with a clutch release arm 26. The rocking of the lever causes the cam to bring the release member into or out of position to engage the latch 22. The arrangement is such that the shaft will always complete its revolution before becoming disengaged from its driving pulley.

The clutch is also arranged to be disengaged by a solenoid 27, Fig. 3, hereinafter called the automatic stop solenoid. The core of this solenoid is connected, by a link 29, with manually operable lever 24, so that the operation or energization of the solenoid will cause the release arm to be positioned to engage the latch 22 and disengage the shaft from the pulley. The shaft 21 is drivingly connected by suitable bevel gearing 31 with a longitudinally extending power shaft 32, and is also connected, through suitable change speed gearing 33 with a shaft 34. The shaft 34 is connected by bevel gearing 35 with a second longitudinal shaft 36. The various gears are so arranged that the shaft 36 is driven at one-half the speed as the power. The purpose of this will be hereinafter set out.

Address printing device feed mechanism

The printing device feed mechanism is arranged to draw the bottommost printing device from a stack in a magazine 40, carried by the frame 30, and progress the device forwardly in four steps to the printing position along a guideway 41. As shown in Figs. 7 and 9, sprockets 42 and 43 are journaled on suitable shafts at the front and rear respectively of the guideway and suitable sprocket chains 44 are carried by the sprockets and are equipped with lugs 44a adapted to engage the rear edges of the printing device and progress them forwardly from the magazine 40 along the guideway 41. As the printing devices are moved from the printing position, they pass downwardly from the forward sprockets 43 into 75

a storage magazine L (Fig. 3) mounted in the usual manner below the machine frame 30. The usual packer mechanism (not shown) may be provided to pack the devices in such magazine.

The sprocket chains 44 are intermittently driven. A forward sprocket 43 is provided with a series of outwardly extending pins 45 arranged to be successively engaged by a pawl 46 carried on the forward end of a bell crank 47 which is secured to a shaft 48 journaled in the machine frame 30. The other arm 49 of the bell crank is connected by a link 50 with an arm 51 pivotally mounted as at 52 to an upstanding frame bracket 53. The arm 51 is provided with a pair of rollers 54 and 55 arranged to engage respective cams 56 and 58 drivingly connected to the power shaft 32. These cams cause the oscillation of the bell crank 47 and the intermittent progressing of the chains 44.

The printing device feed is controlled by a solenoid 57, hereinafter called the printing device solenoid. The core of this solenoid is connected by a link 60 with a lever 61 which is provided with a member 62 arranged as shown in Fig. 7, to engage the pawl 46 and prevent it from picking up a pin 45 so that the sprocket chain 44 will not be advanced unless the solenoid 57 is active to withdraw the member 62. A manually operable member such as a lever 63 is connected by a link 64 with an arm 65 of the lever 61 so that the stop 62 may be locked in an inactive position and the plate feeding mechanism set to function as long as the power shaft 32 is in operation, regardless of the energization of the solenoid 57.

Printing mechanism

The printing mechanism is best illustrated in Fig. 7. Printing is accomplished by bringing a platen P downward into contact with the paper superimposed above the printing device D which is in printing position in the guideway 41. A suitable inking ribbon is interposed in the usual manner between the printing device and the paper or material being printed and will be hereinafter described in detail.

The platen P is mounted on one end of a stamper arm 70, which is pivoted as at 71 to the machine frame, and is provided with a pair of rollers 72 and 73 arranged to engage the respective cams 74 and 75 rigidly secured to a sleeve 76 rotatably mounted on the power shaft 32 and selectively driven thereby to cause the platen to be raised and lowered into and out of contact with work.

Electric selector

The platen is selectively controlled by a solenoid 77 (Fig. 9). The core of this solenoid is connected by a link 78 with an arm 79 pivotally mounted on a suitable frame bracket and the outer end of which engages a collar 80 on a link 81 consequent upon the energization of the solenoid drawing the link downwardly. The upper end of the link is pivotally connected to a latch 82 which acts to restrain the movement of a spring pressed cam arm 84, which carries a roller 85 arranged to normally maintain the upper end 86 of a pivoted arm 87 cammed into position to engage a latch 88 pivotally supported as at 89 on a driving disc 90, which is secured to the power shaft 32. The arm 86 acts to cam the latch 88 out of engagement with a lug 91 of the cam sleeve 76, heretofore described.

When the energization of the solenoid 77 swings the latch 82 clockwise out of contact with the

member 84 withdrawing the roller 85 from contact with the arm 86 permitting the latter to move under the influence of gravity out of the path of the latch 88, the cam sleeve 76 will make one complete revolution, causing the platen to make an impression from the printing device which is in printing position.

Mechanical selector

A mechanical selector is provided to enable the printing from selected printing devices dependent upon the presence or absence of index tabs in the two left-hand tab positions of the printing device, indicated at d4 in Fig. 13. This selector generally is not used in conjunction with the identification mechanism, but enables the addressing machine to be utilized as a standard selective addresser. The mechanical selector includes a detector which acts upon the printing device in the G position of the device on the guideway 41, this position being one step in advance of the printing position H. As shown in Fig. 9, the detector comprises a series of changeable pin members 95 which are carried in a bracket 96 pivotally mounted in a second bracket 97, which in turn is pivoted as at 98 to the frame 30. A suitable tension spring 99 is interposed between the two brackets to normally maintain the bracket 96 in contact with a pin 100 carried by the bracket 97 and causes the two brackets to swing as a unit about the pivot 98. After a printing device has come to rest in the G position and the platen mechanism has started to act on the printing device in the H position the bracket 97 is swung to cause the pin 96 to engage a tab (if there is a tab present), on the printing device in the G position. As shown in Fig. 7, a lever 101 is secured to the shaft 48 which is oscillated by the bell crank 47 as heretofore described. Pivoted to the upper end of the lever 101 is a link 102 carrying a roller 103 arranged to engage on its forward movement an arm 104 secured to the bracket 97 to swing the bracket in a clockwise direction against the action of a suitable spring.

When a tab is present in the path of a pin 95 the swinging of the bracket 96 will be interrupted and due to the resilient connection with the bracket 97 the latter may continue in its movement swinging the pivotal connection 105 between the two brackets downwardly thereby causing the bracket 96 to swing in a counter-clockwise direction. This swinging of the bracket 96 causes a downward movement to be imparted to the link 81 which, as shown in Fig. 9, is pivotally connected as at 106 to the bracket 96, whereupon the latch mechanism 82, 84, 85, 86, is actuated as heretofore described to permit the latch 88 to cause the platen to be actuated. If, however, no tab is present below a pin 95 of the bracket 96 the two brackets move as a unit, the bracket 96 moving therefore in a clockwise direction, which simply causes the link 81 to move upwardly a slight amount and has no effect on the latch mechanisms or platen; hence, when the mechanical selector is used, without the electric selector, hereinafter to be described, printing is accomplished only when predetermined tabs are present.

When the identification system is used, the arrangement is such that the mechanical selector may be thrown out of operation by merely swinging the link 102 (Fig. 7) counter-clockwise about its pivotal connection with the lever 101. This prevents the roller 103 from ever contacting with the bracket 97, in which case the printing opera-

tion is dependent on or is rendered active only when the solenoid 77 is energized.

Whenever the latch mechanism 82, 84, and 85 has been rendered active to permit the latch 88 to actuate the platen operating mechanism, it is automatically reset before the platen completes its cycle of operation and before the solenoid 77 of the detector unit again functions. As shown in Fig. 9, the driving disc 90 is provided with a cam or lug 110 which, once in each cycle of operation, when the latch member 84 is released, contacts with an arm 111 thereof, positively swinging the arm in a clockwise direction about its pivot against the action of a spring 112, whereupon the weight of the bracket mechanism 96 and 97 through the medium of the link 81 positions the latch 82 to engage the latch 84 consequent upon the release of the member 111, by the cam 110, due to the rotation of the disc 90, thus restoring the latch mechanism. The platen therefore remains active to make one impression for each time the latch mechanism is actuated either by the solenoid 77 or the mechanical selective bracket members 96 and 97.

25 Identification or comparison mechanism

The identification mechanism about to be described comprises a series of switch members which are intermittently, mechanically brought into a coacting relation with the identification tabs on each printing device while it rests in the identification position F in the guideway 41 of the addressing machine. This mechanism causes the switch members thereof to be actuated by the identification tabs to set up electrical circuits, which to be effective, must correspond with the circuits set up by the identification mechanism which coacts with the control cards, as will be hereinafter described in detail. At the present time suffice it to say that a series of switches 120 are carried by a block or member 121 pivotally mounted as at 122 to the frame 30. Certain of these switches are normally open and certain of them are normally closed, as will hereinafter become apparent from the description of the circuits with reference to the electrical diagrams. Each switch is adapted to be moved from its normal position by an individual plunger 123 which is slidably mounted in the block 121 and is arranged to be actuated by respective levers 124 pivotally mounted as at 125 to the block 121 and normally held out of contact with their respective pins or plungers by springs 126. The block 121 is rocked about its pivot to bring the levers 124 into contact with tabs T (if such tabs are present), on the printing device in the position F. Consequent upon the rocking of the block, the movements of those levers 124, which engage tabs, are arrested causing the continued movement of the block to bring the plungers 123 into contact with such levers and moving the corresponding switches out of their normal positions. The remaining levers, however, swing as a unit with the block and enter slots or recesses 128 in the frame 30 and do not affect their corresponding switches.

The block 121 carrying the identification switches is rocked by the arm 101 heretofore described, in connection with the mechanical selector. When the arm 101 swings forwardly (Fig. 7), a pin 127 thereof engages the hooked end of a lever 129 which is pivoted as at 130 to the block 121 and swings the block clockwise about its pivot 122 causing the levers 124 thereof to engage such tabs as are present on the printing device in

the F position. As hereinafter described, unless these tabs correspond with the perforations in the card which is at this time in the identifying position F!, in the card feeding mechanism, the automatic stop solenoid 27 is energized, causing the disengagement of the main clutch from the driving pulley 20, thereby stopping the entire mechanism of the addressing machine.

Sheet feed mechanism

The sheet feed mechanism is arranged to feed a sheet, for instance an invoice having the amounts previously printed thereon by a billing machine,—from a stack, progress it across the table of the addressing machine, bring it to a stop in printing position and, after receiving the impression, progress the sheet from the addressing machine to a suitable conveyor or stacking mechanism. Generally, a sheet comprises both an invoice and a stub. The sheet feed is operated at half the speed of the printing mechanism to enable an impression to be made on both the invoice and the stub.

As shown in Fig. 3, the sheets are carried in a suitable stack S at the right-hand end of the machine; a suction arm 140 is intermittently swung into contact with the innermost sheet in the stack by suitable linkage 141, which is operated by a cam 142 carried by the shaft 34. A partial vacuum or suction is applied to the arm 140 in the usual manner causing it to grip the lowermost sheet in the stack and draw it into bite of a pair of feed rolls 143 and 144, which grip the sheet and feed it onto moving belts 145, the sheets being held in contact with the belts by guiderails 146. These belts act to progress the sheets across the table 147 of the addressing machine. The belts 145 are looped around suitable pulleys 148 and 149 located tangentially relative to the table and at opposite ends thereof. Suitable idler rolls 150 carried by arms 151 pivotally connected as at 152 to the machine frame 30 serve to maintain the belts taut at all times. The pulleys 148, as well as the various feed rolls, are rotated continuously by gears 153 carried by their respective shafts and driven from a gear 154 carried by the shaft 34, heretofore described. As this shaft rotates at one-half the speed of the printing mechanism power shaft 32, only one sheet is fed for every two operations of the platen. Hence, two impressions are made on each sheet.

While the paper feed belts 145 tend to continuously move the sheets R, the latter are nevertheless stopped in printing position, as shown in Figs. 3 and 5, and for this purpose I provide a series of stop arms 160 pivoted to a shaft 161 journaled in suitable frame brackets. These stop arms carry on their outer ends stop fingers 162, which consequent upon the rocking of the levers are projected into the path of the moving sheets and restrain the latter against movement until the fingers are raised. The stop arms 160 are raised and lowered by a series of cams 163 rigidly secured to the shaft 36, heretofore described, and which cooperate with suitable rollers 164 carried by the arms 160, suitable springs 165 serving to maintain the rollers in contact with their respective cams. Certain of the stop arms follow the action of other stop arms, so that a sheet is stopped first in one position and then in another position relative to the platen to enable two impressions to be made on each sheet.

The sheet feed mechanism is controlled for operative actuation by the selector mechanism

which controls the platen, that is, the solenoid 77, or by the mechanical selector. The mechanism for effectuating this control is best illustrated in Figs. 5 and 9, and as there shown the cam arm 84 which has a longitudinally extending bar 170 provided with a roller 171 arranged to engage an arm 172 pivoted as at 173 to the frame bracket 53. This arm acts as a clutch release member. The arm extends as shown in Fig. 5 downwardly, and is provided with an arcuate portion 174, which is normally in the path of a latch 175 interposed between the shaft 21 and the change speed gearing 33. As shown in Fig. 5, the latch is pivoted as at 176 to one of the gears of such gearing, and it is normally maintained in engagement with the shaft 21 by a suitable spring, (not shown). The member 174 however acts to prevent the shaft from picking up the latch. When, however, the cam member 84 is actuated to permit the operation of the platen, it swings the roller 171 in a direction to permit the arm 174 to fall out of the path of the pawl 175, thereby permitting the shaft to pick up the latch 175 and drivingly connect the shaft 21 with the change speed gearing and therefore the sheet feed.

Web feeding mechanism

It is often desirable in place of the sheet to utilize a web feed, as in this instance, when invoices are printed in duplicate, only one impression need be made since two webs may be simultaneously fed one above the other into printing position with a suitable carbon or other transfer medium interposed between the two sheets to effect an impression on the second web at the same time the impression is made on the first web. When this feed is used, the clutch mechanism 174, 175 etc. is thrown out of operation by a suitable manual control lever and the entire sheet feed mechanism rendered inoperative.

Such a web feeding mechanism is illustrated in Figs. 1, 2, 7, and 8. In Fig. 2 I illustrate a frame or frame bracket 180 as secured to the addressing machine. This frame 180 has in its lower region a pair of outwardly extending brackets 181 and 182 arranged to receive rolls of paper 183. The frame 180 has at its upper end bracket members 184 and 185 arranged to receive rolls 186.

The webs are fed substantially parallel with each other from the two rolls 183 across the table top of the addressing machine past the printing position and to the two rolls 186 on which the printed webs are wound. The webs pass from the rolls 183 around respective tension pulleys or rollers 190 upwardly through a detector unit 191 and thence over rollers 192 (Fig. 8), which together with rolls 193 maintain the webs in contact with respective feed rolls 194 which regulate the amount of web fed. The rolls 193 are so arranged that the two webs pass between such rolls and across the table top, and are held in engagement therewith by suitable rollers 195 so that an impression may be made on the webs. The webs then pass upwardly around guiding rollers 196 to the respective take up rolls 186 heretofore mentioned. The feed rolls 194 as well as the pick up rolls 186 are positively driven. As shown in Fig. 2, the power shaft 32 is provided with an eccentric disc 200 which is engaged by a connecting rod 201 to oscillate a bell crank 202 pivotally mounted to the frame 180, as at 203. One arm of the bell crank is pivotally

connected as at 204 with a rod 205 which engages respective bell cranks 206 provided with segmental gear portions 207, which are arranged to engage pinions 208 to operate through the usual ratchet and pawl mechanisms generally indicated at 209 to rotate the respective take-up rolls 186. The arrangement is such that the arm 205 is moved a maximum distance with each rotation of the shaft 32, but serves to rotate the rolls 186 only such amount as is required to maintain the webs taut. For this purpose the rod 205 slidably engages the bell cranks 206 and the latter are resiliently maintained in contact with the abutments 210 of the rod by springs 211, which encircle the rod. The active movement of the rod is imparted to the respective bell cranks through the springs 211.

A similar arrangement is utilized to drive the feed rolls 194. A second cam 212 which is carried by the platen cam sleeve 76 operates through a connecting rod 213, a lever 214, a link 215 to actuate a segmental gear 216 and through such levers and in addition thereto a bell crank 217 and rod 218 to actuate a segmental gear 219, immediately following each actuation of the platen. The gear members 216 and 219 actuate respective feed rolls 194 through the usual ratchet mechanism 220. In this instance the operative movement of the segmental gears is accomplished through springs 221 arranged in a manner similar to the springs 211 heretofore described.

An arrangement is provided whereby the web feeding is operated to advance the web so as to position the impression made by the addressing machine accurately relative to impressions previously made, or subsequently to be made, on the web by another mechanism such as a billing machine. This is accomplished through the detector unit 191, which cooperates with a series of perforations made at predetermined points in the web, there being one perforation for each impression which is made on the web by the addressing machine.

The detector unit comprises or includes a pair of spring switch members 225 supported to engage respective webs and consequent upon the alignment of perforations with such fingers, to establish a possible circuit between electrical conductors 226 and 226a and a common conductor 470. The conductor 226 controls a circuit to a solenoid 227 and the conductor 226a to a solenoid 227a. The cores of these solenoids are connected by respective links 228 to levers 229 which are pivoted respectively to the frame 180 at 230. Each lever 229 is provided with a ratchet like claw 231 arranged to engage respective ratchets 232 rigidly secured to the shafts 233 of the respective feed rolls 194. Consequent upon the energization of these solenoids their respective claws 231 engage respective ratchets 232 instantaneously stopping them, thereby stopping the webs accurately so that the impressions made by the addressing machine will align with other subject matter on the web. The timing of these detector units is controlled by cams and switches herein-after to be described in connection with the electrical diagrams. Before the webs are again advanced the claws 231 are positively withdrawn, and for this purpose the pivot 240 for the segmental gear 216 (Fig. 2) extends through the frame member 180, and is rigidly secured to the gear member. On the inner side of the frame member 180 (Fig. 8), a cam 241 is secured to the pivot pin 240. This cam coacts with rollers 242 carried by respective arms 243 of the claw mem-

bers 231, and serves to withdraw the claws from their respective ratchets.

Inking ribbon

5 The ribbon feeding mechanism comprises two separate ribbon-feeding mechanisms, one of which is used when either the sheet feed or the web feed is used, the other of which is used only when the web feed is used. The first ribbon-
10 feeding mechanism comprises a ribbon 250 wound on suitable spools supported as shown on Fig. 3, on suitable frame brackets 254, beneath the table of the addressing machine. The ribbon extends from the spool 252 over suitable guides 255, across
15 the printing device, in the position H on the guideway 41, thence across a similar guide 255, to the other ribbon roll 252.

As shown in the drawings, the ribbon feed is operated from a cam 256, on the shaft 21, the cam coacting with a roller 257 of a bell crank 258, pivoted as at 259 to the frame 30. The bell crank is connected by a link 260 with another bell crank 261, which is provided with a pawl 262 arranged to engage a ratchet 263, drivingly connected to the shaft supporting the rolls 252, thereby causing the ribbon to be intermittently fed once during each rotation of the printing mechanism. The arrangement of the cam mechanism is such that the ribbon is fed as the platen 30 rises from contact with the plate.

Any suitable reversing mechanism may be used to automatically reverse the direction of the ribbon feed. Such reversing mechanisms being well known, no illustration is deemed necessary. The 35 ribbon feed just described passes immediately over the printing device and is interposed between the printing characters thereof and the sheet or the lower web to be printed.

When a web feed is used, (see Figs. 1, 2, and 7), 40 a second inking ribbon or carbon transfer ribbon 270 is interposed between the two sheets, and to prevent offsetting on the upper surface of the web W1 during the printing impression, a ribbon of material, such as cellophane, is interposed between such web W1 and the inking ribbon 270. The cellophane ribbon is indicated at 280.

As shown in Figs. 1 and 7, the inking ribbon 270 is mounted on suitable spools or rollers 272, located at opposite sides of the printing device 50 runway 41. The ribbon 270 is drawn from the left-hand roll 272 around a suitable guide 273 and between the two webs W1 and W2, thence around a guide 274 upwardly to the right-hand ribbon spool 272. The spool 272 is driven by an arrangement similar to that described in connection with the ribbon 250. As shown in Fig. 1, the shaft 21 is provided with an eccentric 275, which is engaged by a connecting rod 276. This connecting rod by means of mechanism, such as a bell crank 277, connected therewith (see Fig. 7) operates a pawl 278, which is arranged to engage a ratchet 279, drivingly secured to the right-hand ribbon spool 272, and thereby cause an intermittent partial rotation of the ribbon spool during the time that the paper webs are being fed.

The cellophane ribbon or band 280, which protects the lower web W1 against offsetting during the impression, is best illustrated in Figs. 1 and 70. As there shown, the band is supported in suitable ribbon spools 282, located above the respective ribbon spools 272. The cellophane band passes from the upper left-hand ribbon spool 282 downwardly into contact with the ribbon 270 and around the guide 273, across the guideway 41, be-

tween the ribbon 270 and the lower web W1, thence around the guide 274 and upwardly to the right-hand ribbon spool 282. The cellophane band is intermittently progressed in step with the ribbon 270. As shown in Fig. 7, a suitable link 284 is connected between the bell crank 277 of the ribbon feed mechanism and a similar bell crank 287 of the cellophane band feed mechanism. A suitable pawl 288 is pivotally connected to the bell crank 287 and arranged to coact with a ratchet 289 in a manner similar to that described in connection with the ribbon feed mechanism.

Card feed

The card feed mechanism is best shown in Figs. 15 11 and 12, and is operated in timed relationship with the addressing machine, being controlled by a suitable cam on the power shaft thereof, as will be hereinafter described in connection with the 20 electrical diagram of Fig. 16. The card feed mechanism comprises a frame 300, and is arranged to feed the bottom card from a stack in a magazine 301, intermittently to an identifying position F1; a selecting position G1; and finally 25 discharge the card into a magazine 302 at the right-hand side of the frame 300. As shown in Fig. 12, I position beneath the magazine 301, a feed plate 304, provided with an upwardly extending abutment 305, arranged to engage the 30 lowermost card in the stack and progress it forwardly (towards the right, Figs. 11 and 12) into the bite of a pair of feed rolls 306. The rolls 306 engage the card and pass it onto a feed plate 307. The progress of the card, as it reaches the feed 35 plate, is interrupted by frictional engagement with contact springs 308 carried by a support 309 secured to the frame, and hereinafter to be more completely described in connection with the electrical diagram. The feed plate 307 is reciprocated, and as the card is engaged by the spring 40 contact members 308, suitable abutments 310 on the feed plate engage the rear end of the card, and force it beneath the contact members and accurately position the card relative to such 45 members.

While the card is in the position F1 on the feed plate 307, the plate is held stationary and the contact members energized, as will be hereinafter described, whereupon the identification 50 circuits operate to determine whether or not the card agrees with the printing devices in the position F on the addressing machine, and if it does agree the mechanism continues to function in repeated cycles.

After the card has been properly identified, the feed slide 307 is operated to move the card forwardly into the bite of feed rolls 311, which pass the card to a second pair of feed rolls 312, the latter rolls serving as did the rolls 306 to pass 60 the card to a feed plate 317. Here the card is interrupted by a second set of contact members 318, which control the selector solenoid 77 of the addressing machine, as will be hereinafter described. The feed plate 317 is provided with an 65 abutment 320 which positions the card beneath the contact mechanism, as heretofore described in connection with the abutment 310 of the feed plate 307. After the card has been positioned, this feed plate is brought to a stop simultaneously 70 with the stopping of the next succeeding card in the identification circuit position F1. The selector circuits are then energized to determine whether or not the corresponding printing device should be printed from. After such circuits have 75

served their purpose, the feed plate 317 is moved forwardly (to the right in Fig. 12), to progress the card into the bite of pairs of feed rolls 321, which serve to feed the card onto a stack 322 in the magazine 302, the stack being lowered from time to time by any suitable means.

The various feeding plates 304, 307, 317, are operated by a suitable cam mechanism. As shown in Fig. 12, a cam 325 is rotatably mounted on a shaft 326 supported in the frame 300. This cam cooperates with a roller 327, carried by a slide bar 328, mounted in suitable guideways in frame brackets 329. A spring 330 serves to maintain the roller in contact with the cam. The slide bar 328 has a pin and slot connection 331, with a lever 332 pivoted as at 333 in the machine frame, the upper end of which lever has a pin and slot connection 334 with a depending lug 335 carried by the feed plate 304, which feeds the cards from beneath the stack into the bite of the rolls 306.

The feed plates 307 and 317 are reciprocated by a second cam 340 which is drivingly secured to a gear 341 journalled on a shaft 342 supported by the frame member 300. This cam cooperates with a pin or roller 344 carried by a lever 345, one end of which is pivoted as at 346 to the machine frame, and the other end of which is pivotally connected to a link 347, which is provided with pin and slot connections 348 and 349 with depending lugs 350 and 351, respectively, of the feed plates 307 and 317, respectively. A suitable spring 355 serves to maintain the pin 344 in contact with its cam 340. These plates are insulated from their guideway 352 formed in opposite frame members 300 and from their respective operating mechanisms.

The cam and feed rolls are driven by suitable gearing which is selectively clutched to the shaft 326, the latter being continuously driven in any suitable manner, as for instance, by an electric motor not shown.

In Fig. 12 I indicate a gear 360, as drivingly secured to the cam 325, and which, through an idler gear 361, drives the gear 341 and the cam 340 heretofore mentioned. Suitable gear trains 362 and 363 are interposed between the gears 341 and 360 and respective gears 364 and 365 of respective feed roll units 306 and 311. The upper feed rolls are driven from gears carried thereby and arranged to mesh with the driving gears of the lower feed rolls.

The feed rolls 312, 321, are driven by suitable gears 366, drivingly connected to their respective roll shafts and to gears 365, which are driven by the gear 363, thus causing the simultaneous operation of the various feed rolls and the feed plates.

As heretofore mentioned, the various feed plates are selectively driven under control of a cam hereinafter to be described. Suffice it to say at the present time that this cam operates an electrical switch arranged to energize a solenoid 377 mounted in a frame 300. The core of this solenoid is connected with a latch 378, which, when the solenoid is energized, is withdrawn from engagement with a member 379, permitting a spring 380 to rock such member in a clockwise direction, whereupon a roller 381, carried by the member, is moved in a clockwise direction, permitting a spring 382 to rock a clutch control lever 383 about its pivot 384 out of the path of a latch 385. The latch 385 is pivotally connected as at 386 with a driving disk 387, which is drivingly secured to the shaft 326. This latch is normally maintained in engagement with the recess 387 in

the hub of the cam member 325, by a suitable spring 388. Normally, the clutch release member is in the position shown in Fig. 12, so that it will cause the latch 385 to become disengaged from the cam. When, however, the solenoid is energized, the latch member swings out of the path of the latch, whereupon the spring 388 draws the latch into the recess, causing the various card feeding mechanisms to be operated to advance the cards one step.

The clutch mechanism is so arranged that it operates to feed cards step by step, the latch 385 being in driving engagement with the cam for one complete cycle of operation. As shown, a suitable abutment or tab 390, carried by the driving disk 387, is arranged to engage a lever 391 carried by the member 379 and reset such member, permitting it to be reengaged by the latch 378 before the cycle of operation is complete, thereby restoring the clutch release member 383 to a position to disengage the clutch consequent upon the completion of that cycle of operation.

Electrical circuits

The electrical circuits, in general, control the various operations of both the card-feeding mechanism and the addressing or printing mechanism. As shown in the electric diagram of Fig. 16, several correlated circuits are established to cause the mechanisms to perform their various functions. These circuits are as follows: A comparison circuit which serves to check the cards with the printing devices, which checking determines whether the machine will function in continued cycles of operation, or whether the entire mechanism will be stopped by the automatic stop solenoid, heretofore described. A card feed and automatic stop circuit which controls the feeding of the cards through the card-feeding mechanism and causes the card feed and the printing mechanism to operate the automatic stop whenever the supply of cards becomes exhausted. A plate feed circuit which functions to cause the printing devices to be fed whenever a predetermined card (control or master card) is present in the F1 position of the card-feed mechanism. A selector and platen operating circuit, which operates the platen clutch mechanism heretofore described, and selectively causes the platen to become active. Finally, a supplemental selector circuit arranged to be so positioned as to supplement the platen control circuit which ordinarily functions whenever a control or master card passes through the card feed, such supplemental selector circuit being adapted to cause the feed to function only when predetermined master or control cards pass through the card-feeding mechanism.

Electrical energy is supplied to various circuits through suitable terminals 400 and 401, which are selectively coupled with lines 402 and 403, respectively, by a suitably manually operable switch 404. This switch also serves to cause the power to be supplied to the motors driving the card feed mechanism and the printing mechanism. A series of timing cams 405, etc., serve to cooperate with switch members 406 etc. to cause the various circuits to operate in synchronism.

Card feed circuit

As shown in the diagram of Fig. 16, cams 405 and 405a operate switches 406 and 406a which control the flow of current to identifying units 408, 409, 410, and 411. The circuits of these units will be hereinafter more fully described. Suffice

it to say at the present time, that if a card and a printing device check or compare, that is, if both have the same account indicia thereon, a circuit will be set up in the output line 412 of the identifying unit 411 at such time as the switches 5 406 and 406a are closed by their respective cams. The line 412 energizes the card-feed solenoid 371, heretofore described, thereby causing the card-feed mechanism to be initiated to progress the 10 cards one step as described in connection with Figs. 11 and 12.

Automatic stop circuit

The energization of the card-feed solenoid 371, 15 causes it to open a switch 415 in a circuit 416 between the line 402 and the automatic stop solenoid 27, which is connected to the line 403, consequent upon the operation of the timing switch 406b due to the operation of a timing cam 20 405b, secured to the power shaft 32 of the printing mechanism, heretofore described. The opening of the switch 415 prevents the current from traveling through the circuit 416 to the automatic stop solenoid and permits continued operation of 25 the power shaft 32 of the address printing mechanism.

The card feed circuit is also provided with a supplemental circuit which serves to operate the automatic stop whenever the supply of cards becomes exhausted. As shown, the card feeding circuit 416 is shunted by lines 417 and 418, which 30 lead to respective contact members 419 and 420, carried by a suitable insulation member beneath the stack of cards in the magazine 301 of the 35 card feed mechanism. When the last card in the magazine has been removed therefrom, a suitable contact member 421 carried by an insulated weight member 422, superimposed above the stack, serves to close the circuit between the two 40 contact members 419 and 420, thereby energizing the automatic stop solenoid independent of the operation or function of the identifying or card-feed circuit.

Plate feed circuit

The plate feed circuit, which includes the solenoid 57, as heretofore mentioned, controls the functioning of the feed chain 44, and is illustrated in Fig. 16. As there shown, one pole of the 50 solenoid 57 is connected with the power line 402 through a switch 406c arranged to be closed by a cam 405c secured to the power shaft 32. The other pole of this solenoid is connected by a line 423 with a contact brush 424 carried by the contact plate holder 309 of the card feeding mechanism and which is arranged to engage the perforation M in the card C (if such perforation is 55 present when a card comes to rest in the position F1 of the card feeding mechanism). If such a perforation is present in the card, the contact member 424 extends therethrough and contacts with the plate 307, which is insulated from the various parts of the card feeding mechanism, but is connected by a suitable conductor 425 with the 60 other power line 403, thereby causing an energization of the plate feed solenoid whenever a master card is present in the F1 position of the card feed mechanism.

Platen operating circuit

The platen operating circuit is, as shown in 70 Fig. 16, connected to the power line 402 by a switch member 406d through the medium of a cam 405d rigidly secured to the power shaft 32 of a printing mechanism. This switch is con-

nected by a line 426 with a contact member 427 which may be engaged by a contact member or switch 428 which will hereinafter be described in connection with the selector circuit. However, if a contact is made between the members 427 and 428, a circuit will be made through a line 429 to one pole of the platen operating solenoid 77, the other pole of which is connected by a line 430 with the line 423 of the plate-feed circuit and consequent upon the presence of perforation M in the card in the F1 position, current will flow through the contact member 424 to the other power line 403, thereby establishing a circuit and causing the platen operating solenoid 77 to withdraw the latch relief member 87 from the path 15 of the latch 88, permitting the power shaft to pick up the platen operating cams, thereby causing an impression to be made.

Selector circuit

The selector circuit controls the operation of the switch members 427 and 428, which must be closed in order for the platen circuit to effectively operate. As shown in Fig. 16, the selector circuit comprises a line 431 which is intermittently connected to the power line 402 by a switch member 406e arranged to be controlled by a cam 405e, drivingly carried by the power shaft 32. The line 431 is connected to one pole of a solenoid 437, the other pole of which is connected by a line 438 with a switch member 439, which in turn is connected to the power line 403. Consequent upon the operation of the timing cam 405e, the selector solenoid is energized.

The energization of the selector solenoid with- 35 draws a spring-pressed latch 471 from engagement with a pivoted lever 473, carrying the contact 428, permitting a spring 474 to bring the contact members 428 and 427 into engagement with each other. This does not complete the 40 circuit, but merely allows the completion thereof, when the next master or control card appears in the identifying position F1 in the card feed mechanism, which may be only after the feeding of several service cards. The circuit is therefore 45 held ready after the solenoid 437 is deenergized and until a master card appears in the F1 position. This is accomplished by completing the circuit only through the master card perforation M, as heretofore described, and resetting the 50 latch only after such completion has been effected. The resetting is therefore made by the plate feed solenoid 57, the core of which is connected to a bar 475. This bar is provided with a lug 476 arranged to engage an arm 477 of the lever 55 473 and move such lever into position to be re-engaged by the spring pressed latch 471. The timing cam 405d which controls the plate clutch circuit is set to close and open its switch 405d before the timing cam 405c operates to close the 60 switch 406c which establishes the circuit to the plate feed solenoid 57, thereby preventing circuit feed backs and insuring the operation of the platen before the plate feed is effected.

Supplemental selector circuit

The supplemental selector circuit utilizes the perforations in the column J of the control card. When this supplemental selector system is used, the switch 439 is opened, breaking the circuit 70 between the line 438 and the power line 403. The line 440 is then connected to the line 438 as shown in Fig. 16, and to a series of brushes 318 heretofore described in connection with Figs. 11 and 12. These brushes are in parallel cir- 75

cuits with each other, and are arranged, if there is any perforation present in the area J, to contact with the feed plate 317, which is connected by a suitable line 441 with the power line 403. Hence, when this system is used, the selector solenoid 437 will only be energized when there is a perforation in the area J, and hence the platen operation mechanism will function only for those control or master cards which have a perforation in the column J, as well as the usual master card perforation M, carried by all master cards.

Web feed control circuits

As shown in Fig. 16, there are two web feeding control circuits. One of these circuits functions to energize the solenoids 227 and 227a, heretofore described, which act to stop the web feed accurately so as to align the imprint made by the address printing mechanism, with imprints previously made on the web heretofore explained. A line 470 leads to the two contact fingers 225, which coat with the web perforations to energize their respective solenoids, and is intermittently connected by a suitable switch 406f with the power line 402 by a cam 405f drivingly mounted on the platen driving sleeve 16, heretofore described, in connection with the platen-operating mechanism of the addressing machine. To complete the circuits, the solenoids 227 and 227a are connected by suitable lines 470a with the other power line 403, thereby energizing the solenoids whenever the switch 406f is closed by its cam. As the switch 406f is operated by a cam on the platen operating sleeve, this circuit will only be energized when such sleeve is rotated, in other words, only once for each time the platen clutch control circuit is operated by the solenoid 11. The timing is such that the webs are stopped by the solenoids 227 and 227a before the platen makes its impression.

A second web feed control circuit is provided which serves to stop the entire mechanism consequent upon the breaking or exhausting of the web. As shown in Fig. 16, I have provided a pair of contact fingers 445 and 445a, arranged to engage respective webs W1 and W2. If at any time a web breaks or becomes exhausted these contact fingers will coat with respective contact members 446, which are connected by lines 447 with the line 416 of the card feed control circuit, which, as heretofore described, will energize the automatic stop solenoid 27, thereby stopping the address printing mechanism. Each of the spring contact fingers 445 and 445a are connected by a suitable line 448 which is intermittently connected to the power line 402 by a suitable switch 406g arranged to be intermittently actuated by a cam 405g rigidly secured to the platen operating sleeve 16. This cam, being likewise carried by the platen operating sleeve, causes this circuit to be energized only when the platen and paper feed mechanism operate.

General circuit detail

The timing of the various cams is illustrated by the timing diagram of Fig. 30, the various operations being described thereon for one complete cycle. As this diagram gives the relationship of the beginning and end of the various active operations of the circuits and mechanisms, they will not be described in detail. The inscriptions on the diagram have been made in accordance with the specification.

While I have described the automatic stop

mechanism as stopping the addressing machine, it is obvious that it also stops the operation of the card feed mechanism. The card feed mechanism depends, as previously described, upon the actuation of the switch 406b in Fig. 16. This switch is controlled for operation by the cam 405b which is carried by the power shaft 32 of the address printing mechanism. Hence, the stopping of the address printing mechanism will automatically stop the card feed mechanism, as the shaft 32 always comes to rest in a position in which all of the switches 406 etc. are open. The arrangement of the various clutches and mechanism is such that the apparatus controlled thereby will go through a complete cycle of operation before their various clutches are released. The same is true for the automatic stop clutch, as has been heretofore described in connection with the address printing mechanism.

Each of the solenoids, shown and described, is preferably provided with a safety switch mechanism. This mechanism, while not described in detail, is apparent from reference to Fig. 8. Here it will be noted that each solenoid is provided with a switch 450, which is placed in series with the solenoid circuit and is operated by the core thereof. The arrangement is such that the switch is normally closed, but when the core is actuated, serving to break the circuit through the solenoid shortly after it has been energized. While certain of the solenoids demand operation over a continued period of time, it is obvious that these switches operate as vibrators, energizing and deenergizing the solenoid with great rapidity, but at the same time protecting them against overload, due to the current being on the windings thereof, for an abnormal length of time.

In starting the mechanism, the card and printing device feeds may be operated in any well-known manner, for instance, by suitable by-pass switches (not shown) or by merely manually operating the respective clutches until a card and a corresponding printing device are in their respective identifying positions F¹ and F, at which time the main switch 404 may be thrown to operate the mechanism automatically.

The operation of the automatic stop serves to give either a visible or audible signal, or both, whenever it stops the mechanism. As shown in Fig. 16, the solenoid 27 which operates the automatic stop clutch also operates a switch 505 in a circuit 506 between the power lines 402 and 403. A suitable visible signal, such as a light 507 (or a bell, not shown) is placed in series with the circuit 506. Hence, such signal will be energized whenever the automatic stop is operated.

Duplicating circuits

The duplicating circuits are used only with a sheet feed. When the sheet feed is used, it is customary to print twice on the same sheet for the invoice and the stub. Hence, the mechanism will be set for duplication, that is, to make two impressions on each sheet, whereas when the web feed is used, one web is disposed above the other, and two impressions are made on the same platen stroke.

When the sheet feed is used, switches 451 and 452 in the lines 470a and 447 of the web feed circuit are opened, rendering these circuits inactive. Hence, the condition of the web will not act to cause the operation of the automatic stop solenoid 27. It is, however, necessary to so arrange the mechanism that following the first impression the automatic stop, the card feed cir-

cuit and the plate feed circuits, will be retained open, so that no card or plate will be fed during the cycle in which the second impression is initiated. For this purpose I utilize cams 455a and 5 455b. These cams are arranged to control switches 456a, 456b, in the automatic stop and card feed circuits respectively.

The cams 455a and b are rigidly secured to the shaft 36, which, as heretofore mentioned, rotates at one-half the speed of the power shaft 32 10 to which the cams 405 etc. are secured. The cams 455a etc. are so arranged that when the sheet feed is operated, they will be ineffective for one-half of the revolution of the shaft 36, 15 that is, when the shaft 32 is making its first cycle to initiate the first impression, it will then become effective to open the circuit during the next half of the revolution of the shaft 36 or the next cycle of operation of the power shaft 32, thereby 20 preventing the plate feed and the operation of the automatic stop during the initiation of impressions. The operation of the circuits during the initiation of the first impression is the same as for the web feed. For the second impression, 25 however, the automatic stop is interrupted so that both impressions will be made from the same printing device even though the card and printing device were progressed during the cycle in which the platen clutch mechanism was set for the 30 making of the first impression, whether or not the identifying circuits identify the next succeeding device and card now in identifying position. Hence, the cams 455a and b and the switches 35 456a and b are operated to interrupt the automatic stop and card feed circuits during the cycle of operation in which the clutch mechanism is set for the making of the second impression.

If the card fed during the cycle of operation in which the clutch mechanism is set for first 40 impression should be a master card, the second cycle of operation would normally cause the plate feed to operate, therefore a cam 455c, secured to the shaft 36, is arranged to open a switch 456c and open the plate feed circuit so that in the 45 cycle of operation in which the clutch mechanism is set for the second impression no plates will be fed.

To make duplicate impressions since the printing 50 operation is controlled by the selector circuit and the plate feed clutch, it is necessary to energize the solenoid 77 independent of the action of the plate feed solenoid or the selector solenoid. Hence, the line 426 of the plate feed circuit or 55 selector circuit, which is controlled by the cam 405d, is connected by a line 457 with a switch member 456d which is controlled by a cam 455d on the shaft 36 and which in turn is connected to one pole of the solenoid 77. The other pole of the solenoid is connected by the line 430 (heretofore mentioned, which passes to the master card control finger 424) and is bypassed by a line 458, controlled by a switch 456e, operated by a cam 455e, to connect the line 458 with the power line 403, thereby energizing the platen clutch on the 60 subsequent feeding operation. Thus it will be seen that while during the cycle of operation in which the platen clutch is set for the first impression, both the cards and printing devices are fed, the actual printing operation takes place on the next succeeding cycle. During the cycle in 65 which the first impression is made, the cards and printing devices are retained in position.

During such latter cycle of operation, the platen clutch is set to make the second impression, independent of the function of the identification, 70

printing device feed, card feed, or the selector circuits, this second impression being actually effected during the next succeeding cycle of operation of the power shaft 32.

Group or series control

5

As heretofore mentioned, the cards may be in series or groups, each series comprising one or more service cards and a control or master card. When series of cards are used, one address printing device is supplied for each series, or master card, and the service cards are compared, one at a time as fed, with the printing device for that series. The feeding of such printing device occurs only after the passage through the card feed 10 of the master card for such series. My improved mechanism, as is obvious from the preceding description, will automatically adapt itself for the use of one card for each printing device, all such cards being master cards; or for the use of 15 series or groups of cards, each series comprising one or more service cards followed by a master card; or for the use of groups dispersed among 20 successive master cards.

Each master card is provided with a perforation M which, of course, is not present on the service cards, and each card, whether it be a master or service card, is perforated with indicia on the portion K thereof for identification purposes. As a service card of a series reaches the 25 identifying position F1, in the card-feeding mechanism, the contact members 308 and identification circuits, hereinafter more fully described, act to determine whether or not the indicia or perforations in the area K of such card, correspond with the indicia or identification tabs on the printing device in the position F of the printing device feed mechanism. If such indices correspond, the card feed continues to function and the card is 30 progressed to the position G1. As the service 40 cards do not have the master card perforation M, the plate or printing device feed solenoid 57 is not energized by a service card when it is in the position F1 and hence, as heretofore described in 45 connection with the description of the plate feed circuit, the printing plate feed will not be actuated by the service card.

Likewise, as described in connection with the platen-operating circuit, the platen solenoid 77 50 will not be actuated by a service card as it is dependent upon the presence of a master card having a perforation M. Hence, as the service cards of a series are fed, they are each compared with the printing device which remains in the 55 position F until the master card for that series, which follows the last service card in such series, arrives at the position F1 in the card feed. Such master card, however, energizes the plate feed and platen solenoids 57 and 77, as heretofore 60 described, to cause the plate feed and platen to function, advancing the plate and bringing a new plate into the position F of the plate feed to be compared with the next card fed, which card may be either a master card or the first 65 service card of a new series, if a series of cards, rather than a single card, should follow.

The selector circuit which must be energized to permit the platen to effectively operate, as well as the supplemental selector circuit which 70 may be used, if desired, to supplement the selector circuit and provide an additional control of the platen are, as described under their respective headings, energized only by a master card perforation M, hence are not affected by the 75

service cards which do not have such a perforation.

Hence, it is apparent that each service card and the master card of a series or group of cards is compared with the same printing plate and must therefore compare with each other or the stopping of the entire mechanism would result since the automatic stop and card feed circuits, heretofore described, are not dependent upon the presence or absence of the master card perforation M, but are dependent upon the identification circuits, as heretofore mentioned.

Identification circuits

Illustrative identification or comparison circuits are shown in Fig. 17, and the arrangement is such that, when the indicia on a card and a printing device correspond, a general series circuit will, in effect, be established from the power line 402 through the card perforations in the thousands column to the switch operated by a tab in thousands column on the printing device, thence through the perforations in hundreds column to the switch operated by the tab in hundreds column, thence to the perforation in tens column and to a switch operated by the tab in tens column, and thence to the card perforations in units column and to a switch operated by the tab in units column, and finally to the card feed solenoid 371, thus establishing the card-feeding circuit whenever the perforations in the card, in the identifying position in the card feed mechanism, agree or correspond with the tabs on the printing device in the identifying position of the printing device. If the perforations do not correspond with the tabs, this circuit will be broken, in at least one of the columns, and hence there will be no flow of current in the circuit and the switch 415 which controls the automatic stop circuit will remain closed, whereby the automatic stop (22-26, etc.) will function to stop the mechanism, as heretofore described.

Each identification circuit unit comprises a primary circuit and a secondary circuit. The primary circuit includes the switch member 406 which intermittently connects a line 480 with the power line 402 by reason of a cam 405. This line 480 has connected to it, in a parallel arrangement, a series of solenoids or relays 481. The circuit from each individual relay 481 is completed through respective lines 482, which are connected to respective contact members 308, supported as heretofore described in the identifying position, above the cards in the card-feed mechanism. When a perforation in the card aligns with any one of the contact fingers 308, the circuit will be established to the plate 307, which is connected to the return power line 403 by suitable conductors 483, thus energizing the relay associated with any given contact spring entering the perforation in the card.

The relays 481 in each identifying circuit unit 408, 409, 410, and 411 are operated similarly with each other, and each serves to operate independent switch members associated therewith, as will be hereinafter described in connection with the specific identifying circuits illustrated.

The circuit unit 408, is that circuit the contact brushes 307 and 308 of which, coat with the perforations in the thousands column of the card. This circuit unit, as shown, is enclosed by the dotted line marked 408 on the left-hand portion of Fig. 17, and includes two relays 481. This number of relays corresponds to the number of perforation locations allotted to the thousands

column of the card, namely, two (0 and 1). When either relay 481 is energized, due to its respective brush 308, contacting with the plate 307 through a perforation in the card, it serves to close its respective switch 485. One pole of each switch 485 is connected by a line 486 with the power line 402. A suitable switch 406a is arranged to intermittently interrupt this circuit, due to the action of the cam 405a secured to the timing shaft 32, as heretofore mentioned. This cam 405a follows the cam 405 so that the circuit in the line 486 is established slightly after the solenoids 481 are energized. The other poles of the switches 485 are connected by lines 487, with respective switches 120, which are as heretofore described mounted in the block 121 of the addressing mechanism and operated by the tabs on the address printing devices. These switches 120 are in turn connected to a common line 412a, this line being the output line for the unit 408. The switches 120, as will be noted, are normally opened switches, and arranged to be closed consequent upon contact of their respective operating arms 124 with tabs of the printing devices (Fig. 9). Hence, it will be seen that if a perforation exists in any one opening in the card and a tab is in the corresponding position on the printing device, the relay 481 corresponding to such perforation will be energized, the switches 485 and 120 of that corresponding circuit will be closed by the relay and tab, respectively, thereby energizing the line 412a. If, however, the tab and perforations do not compare, that is, for instance, if there is a perforation corresponding to the left-hand relay 481 and a tab corresponds with a right-hand switch 120 (of identifying unit 408) the left-hand circuit will be opened at the switch 120, and the right-hand circuit will be opened at the switch 485. Therefore, the line 412 will be dead, that is, will not be energized.

The identification circuit units 409, 410, and 411, are each identical with each other, and the primary circuits thereof are connected in parallel, and the outlet circuits are connected to the various identifying units in series. The circuits of one of such identifying circuit units are shown within the dotted line enclosure on the right-hand portion of Fig. 17, and as there shown it will be noted that the relays 481 cooperate with the primary circuits in exactly the same manner as the relays 481 of the circuit unit 408. These relays 481 of the identifying circuit units 409, 410 and 411, however, are arranged to operate a pair of switch members, one of these switch members 485a, corresponding in identity and operation with the switch 485, heretofore described, in connection with the identifying unit 408. One pole of each of these switches 485a is connected by a line 486a with the output circuit of the preceding identifying unit, as for instance, in case of the unit 409, with the output 412a of the unit 408. The other poles of these switches are connected, by respective lines 487a, with corresponding switches 120 of the block 121 (Fig. 9) which cooperates with tabs, corresponding in position to the perforations in the cards which are arranged to be contacted by respective spring brushes 308.

The switches 120 are normally open switches and are connected by suitable lines 488 with a common line 489, which by means of a pair of switches 490 and 491, normally held in closed position shown in Fig. 17, by springs 492, and interposed in a series arrangement in said line,

are connected to the output line 412 of the respective identifying circuits.

The functioning of the identifying circuits 409, 410, and 411 for the numerals 0, 1, 3, 5, 7, and 9 is the same as heretofore described in connection with the functioning of the circuit in the thousands column or the identifying circuit 408. Fig. 18 illustrates in heavy lines the circuits, including the lines and switches, energized or moved when the same odd number is perforated on the cards and tabbed on the printing device. The circuits, as shown, are set up for the numeral 5, and it will be noted that in this instance the power line 412 is energized. In Fig. 19, the circuit illustrated in heavy lines is energized when different odd numbers are present on the tab and card in the identifying positions. In this instance it will be noted that the output line 412 is not energized.

As heretofore mentioned, when one of the numerals 2, 4, 6 or 8 is indicated by the perforation in the $\frac{1}{2}$, $\frac{3}{4}$, $\frac{5}{6}$ or $\frac{7}{8}$ positions respectively, there is also a perforation in the $9/+$ position. Likewise, when there is a tab in either of the 1, 3, 5, and 7 positions, which is intended to represent a 2, 4, 6 or 8, respectively, it is accompanied by an embossed tab in the 9 position. Under such circumstances, it is, of course, necessary to prevent the setting up of the circuit which would ordinarily indicate a "9" and it will be noted from Fig. 17 that each of the relays 481 operates a pair of switch members, namely, a switch member 485a previously described, and a normally closed switch member 494. The switch members 494 are connected in series in the line 486a leading to the switch 485a of the right-hand "9" relay of the respective identification unit. Hence, if there is a perforation in the $9/+$ position and any other position, the circuit to the switch member 485a will be interrupted by the opening of one of the switches 494, thereby preventing the energization of the output circuit 412 regardless of the closing of the switch 485a of the "9" relay. The energization of the "9" relay 481, however, also closes a switch member 495, closing a circuit 496 between the power line 403 and one pole of a solenoid 497, the other pole of which is connected by a conductor 498 with the line 480 which is connected to the other power line 402, thereby energizing the solenoid 497 whenever a tab is present in the $9/+$ position of the card.

The energization of the solenoid 497 picks up the switch 490, raising it out of contact with the member 498b of the line 489, into contact with the member 498a on a line 489a. When, however, an embossed tab is present in the 9 position on the printing device, the normally open switch member 120a carried by the block 121 is closed. One pole of this switch member 120a is connected by lines 500 and 496 with the power line 403, and the other pole is connected by a line 501 with a solenoid 502, which, when energized, raises the switch member 491 away from the contact 503 in the line 489 and into contact with a member 504 and the line 489a. The other pole of the solenoid 502 is connected to the line 498 heretofore mentioned, and through the line 480 to the power line 402. It will be noted that both solenoids 497 and 502 are in the primary circuits and hence operate slightly before the secondary circuit 486a etc. which passes through the various switches 120 of the circuit between the relays 481 and the line 489. Hence, the switch members 490 and 491 will be positioned before any current passes through the line 489. Now, when there is a perforation in the card at K, $\frac{5}{6}$ and $9/+$ posi-

tions, and tabs in the $\frac{5}{6}$ and 9 positions, of the printing device, the line 489 will be energized, as noted from the heavy lines in Fig. 22, and as both solenoids 497 and 502 have been energized to pick up their respective switch members 490 and 491, the output line 412 will be energized. 5

As shown, for example, in Fig. 23, when the $9/+$ position in the card is punched, and an embossed tab is in the 9 position of the printing device, and another non-corresponding position in the card and printing device is punched and tabbed respectively, the circuit to the line 489 will be broken, as illustrated in Fig. 23 and the output line 412 will not be energized. 10

When there is a perforation in the 9 position, and any other position in the card, normally representing an even number, as, for instance, in Fig. 24, where perforations are indicated in the $9/+$ and $\frac{5}{6}$ positions, to indicate 6, and the printing device is tabbed for a 7, the circuit will be 20 broken, as illustrated; the switch members 490 and 491, being in opposite positions, thereby opening the lines 489 and 489a, preventing energization of the line 412 through any possible energization of the line 489. 25

It will be seen from the foregoing that the "9" position of the embossed tab controls the solenoid 502 and the switch 491, and that the "9" perforation in the card controls the solenoid 497 and the switch 490. Hence, unless the card and printing devices are perforated and tabbed (with an embossed tab) in the "9" positions, or unless without a perforation and an embossed tab in such positions the switches will be oppositely set. That is, one will be connected with the line 489, whereas the other will be connected with the line 489a, and hence the output line cannot be energized by the line 489. This latter condition exists when the card is perforated in the "9" position only and the device has a plain split tab in the "9" position, 40 both of which indicate a "9". To energize the output line 412 under this condition, the switch 485a of the "9" relay is indirectly connected to the switch 120 of the "9" tab position. As shown, the switch 485a is connected by a line 515 with 45 a normally closed switch 516 carried by the block 121 above the "9" tab position. This switch is in turn connected to the normally open switch 120 of the "9" position, which is in turn directly connected by a line 517 with the output line 412 50 of the respective circuit unit, thus establishing a circuit when the card and plate are each identified as representing a "9". 55

The presence of an embossed tab in the "9" position of the printing device opens the switch 516, thereby opening the "9" circuit to the line 517 and the output line 412. The presence of a second perforation in addition to the $9/+$ perforation in a card opens the corresponding switch 494 and prevents current from reaching the "9" 60 relay switch 485a or the output line 412 through the line 517. Hence, the output line 412 will not be energized by the line 517 unless both card and printing device are identified as a "9". 65

The fragmentary diagrams of Figs. 18 to 26, some of which have been previously mentioned, are generally illustrative of the possible circuits and their effect on the output line 412 which controls the card feed solenoid 371. These diagrams will now be briefly described. Each diagram represents only the $5/6$, $7/8$ and $9/+$ positions, relays and circuits, as these suffice to represent all possible general combinations. 70

Fig. 18 illustrates a card perforated to represent any odd number except a nine and a print- 75

ing device tabbed to represent the same odd number (5). The switches operated and circuits energized are shown in heavy black lines, and as the card and device check the output line 412 is energized and the mechanism continues to function in repeated cycles.

Fig. 19 illustrates a card perforated to represent any odd number except a nine (5) and a printing device tabbed to represent any different odd number except a nine (7). The switches operated, and circuits energized are again shown in heavy black lines, and as the card and device do not check the output line 412 is not energized, and the automatic stop will function to stop the entire mechanism.

Fig. 20 illustrates a card perforated to represent any odd number except a nine (5) and the printing device is tabbed to represent an even number (6). The switches operated and circuits energized are indicated by heavy lines, and as the card and device do not check, the output line 412 is not energized and the mechanism will be stopped.

Fig. 21 illustrates a card perforated to represent any odd number except a nine (5) and the printing device is tabbed to represent a 9. The switches operated and circuits energized are indicated by heavy lines, and as the card and device do not check, the output line 412 is not energized and the mechanism will be stopped.

Fig. 22 illustrates a card and device perforated and tabbed for the same even number (6). The switches operated and circuits energized are indicated by heavy lines, and as the card and device check with each other, the output line 412 is energized and the mechanism will continue to function in repeated cycles.

Fig. 23 illustrates a card and device, perforated and tabbed for different even numbers (6 and 8 respectively). The switches operated and circuits energized are shown in heavy lines, and as the card and device do not check, the output line 412 is not energized and the mechanism will be stopped.

Fig. 24 illustrates a card perforated for any even number (6) and a printing device tabbed for any odd number, except a nine (7). The switches operated and circuits energized are shown in heavy lines, and as the card and device do not check, the output line 412 is not energized and the mechanism will be stopped.

Fig. 25 illustrates a card perforated for any even number (6) and a device tabbed for a 9. The switches operated and circuits energized are shown in heavy lines, and as the card and device do not correspond, the output line 412 is not energized and the mechanism will be stopped.

Fig. 26 illustrates a card and device perforated and tabbed to represent a 9. The switches operated and lines energized are shown in heavy lines, and as the tab and device check, the line 412 is energized and the mechanism will continue to function in repeated cycles.

Fig. 27 illustrates a card perforated for a 9 and a device tabbed to represent any odd number except a nine (5). The switches operated and circuits energized are shown in heavy lines, and as the card and device do not check, the line 412 is not energized and the mechanism will be stopped.

Fig. 28 illustrates a card perforated to represent a 9 and a device tabbed to represent any even number (6). The switches operated, and circuits energized, are shown in heavy lines, and as the card and device do not check, the line 412

is not energized and the mechanism will be stopped.

When the addressing machine is to be used without the identification system, the main switch 404 is opened and the motor 20 operated from a different source of power. The roller 103 and its arm 102 are swung into the position shown in Fig. 7, whereupon the mechanical selector controls the platen and sheet feed clutches, as heretofore described. The manually operable lever 63 (Fig. 7) is swung counter-clockwise, locking the member 62 out of the path of the pawl 46, whereupon the printing device feed will function in repeated cycles. If the web feed is used, current is supplied to the switches 406f and 406g independent of the switches 406 to 406e, thereby permitting proper functioning of the web feed.

I claim:

1. The combination of two series of devices, the devices in each series being supposedly arranged in the same predetermined order, corresponding indicia on the corresponding members of the two series, normally idle means for feeding both series, and means rendered active consequent upon the simultaneous presence in an identifying position of members having corresponding indicia to control such feeding means.

2. The combination of a series of members supposedly arranged in a predetermined order, and a series of related devices supposedly arranged in the same predetermined order, corresponding indicia on related members and devices, and means rendered active consequent upon the presence of a member, and a device bearing such corresponding indicia in an identifying position in the feeding mechanism, to initiate the feeding of the member or device.

3. The combination of a series of control members and a series of printing devices, some of said members and devices bearing corresponding indicia, means rendered operative only consequent upon the presence of a member and device having corresponding indicia thereon in an identifying position in the feeding mechanism, to render the feeding means operative to feed a device.

4. The combination of a series of index devices supposedly arranged in a predetermined order, and a series of related printing devices supposedly arranged in the same predetermined order, corresponding indicia on related index devices and printing devices, feeding means for the devices of one series, power means to operate said feeding means, a clutch interposed between said power and feeding means, means dependent upon the presence of an index device and a printing device bearing corresponding indicia in identifying positions in the respective feeding mechanisms, to render said clutch operative to cause the feeding means to operate.

5. A series of members supposedly arranged in a predetermined order, a series of related printing devices supposedly arranged in the same predetermined order, the related devices and members both bearing corresponding indicia, means to feed the members into an identifying position, means to feed the devices into an identifying position, and means rendered active consequent upon the presence of a member and a device in their respective identifying positions bearing corresponding indicia to initiate the feeding movement of the members and devices.

6. A series of cards supposedly arranged in a predetermined order, a series of related printing devices supposedly arranged in the same predetermined order, the devices and cards both bear-

ing corresponding indicia, means controlled by the indicia on both the cards and devices to feed the cards from an identifying position, means controlled by the cards alone to feed the devices from an identifying position, and means acting consequent upon the presence of a card and a device in their respective identifying positions and bearing non-corresponding indicia to prevent either of said feeding means from functioning.

10 7. A series of control members supposedly arranged in a predetermined order, a series of related printing devices supposedly arranged in the same predetermined order, the devices and members both bearing corresponding indicia, means to feed the cards into an identifying position, means to feed the devices into an identifying position, and electric relays arranged to be energized by respective member indicia, and means controlled by the conjoint action of said relays and the device indicia to initiate the feeding movement of the members.

25 8. A series of control members supposedly arranged in a predetermined order, a series of related printing devices supposedly arranged in the same predetermined order, the related members and devices both bearing indicia representing the same value, a feeding mechanism for the devices, means dependent upon the presence of a member in the identifying position bearing indicia representing the same value and additional indicia to initiate the feeding of the devices.

30 9. A series of perforated cards supposedly arranged in a predetermined order, a series of related address printing devices supposedly arranged in the same predetermined order, the devices having indicia in the form of removable tabs corresponding to perforations in related cards, a feeding mechanism for the devices, means including a primary electric circuit rendered active by the perforations, and a secondary circuit adapted, when energized, to initiate the feeding of the cards, said secondary circuit being independently controlled by the primary circuit and the tabs on the printing devices.

45 10. The combination of control means and printing devices bearing related indicia, means to advance the control means and printing devices in operative synchronism, a primary electric circuit rendered active by the indicia of the devices, a secondary circuit adapted when energized to initiate advancement of said control means, said secondary circuit being independently controlled by the primary circuit and the indicia on the printing devices.

50 11. The combination of a series of control members and a series of printing devices, some of said members and devices bearing corresponding indicia, and means including a relay actuated by the indicia on the members, a switch mechanism actuated by said relay and a second switch mechanism in series with the first-named switch mechanism to feed a control member when the indicia on the members and devices correspond.

55 12. A series of perforated cards supposedly arranged in a predetermined order, a series of related address printing devices supposedly arranged in the same predetermined order, the related cards and devices bearing corresponding indicia, comprising perforations and removable tabs respectively, feeding means for the cards and devices arranged to feed them one at a time into corresponding identifying positions, means dependent upon the presence of a card and de-

vice in the corresponding identifying positions and bearing corresponding indicia to initiate the feeding of the card, and additional means arranged to coact with a perforation in certain of said cards to initiate the feeding of the printing devices.

60 13. A series of cards supposedly arranged in a predetermined order, a series of related printing devices supposedly arranged in the same predetermined order, the related cards and devices bearing corresponding indicia, a normally inactive feeding means for the cards and devices arranged when in operation to feed them one at a time into corresponding identifying positions, means including an electrical circuit dependent upon the presence of a card and device in the corresponding identifying positions and bearing corresponding indicia to initiate the feeding of the card, and additional means including an independent electrical circuit and arranged to coact with certain of said cards to render the feeding means active to feed the printing devices.

65 14. In a machine through which supposedly interrelated printing devices and control devices are intermittently moved in step with each other, means for determining the relation or non-relation of given printing and control devices, said means including an electric circuit and means for rendering the circuit active to determine the operative identity of said printing devices and control devices when the same are at rest in predetermined respective positions in said machine, and a signal operated by said circuit consequent upon non-interrelated devices occupying said positions of rest.

70 15. In a machine through which supposedly interrelated printing devices and control devices are intermittently moved in step with each other, means for determining the relation or non-relation of given printing and control devices, said means including an electric circuit and means for rendering the circuit active to determine the operative identity of said printing devices and control devices when the same are at rest in predetermined respective positions in said machine, and means to prevent further movement of said devices from said respective positions of rest consequent upon non-interrelated devices occupying said positions of rest.

75 16. In a machine through which supposedly interrelated printing devices and control devices of respective sets are moved in step with each other, means to print from said printing devices, detecting means operating at predetermined respective stations of the printing and control devices to determine whether given devices truly correspond, selective means operating on the control devices in another station thereof, and means controlled by the conjoint action of the detecting and selecting means to initiate the operation of said printing means.

80 17. The combination with a series of control members, and a series of related printing devices, the related members and devices having corresponding indicia thereon, certain only of the control devices having additional indicia thereon, a printing mechanism adapted to make impressions from the printing devices, said printing mechanism adapted to be initiated in its operation by said additional indicia only when the related control device and controlled device correspond.

85 18. In a comparison mechanism, wherein a series of master and subordinate control ele-

ments are fed from a stack one by one in such order that the subordinate cards immediately precede the master card corresponding thereto, detecting means to determine whether the subordinate cards are advanced in said order and means to effect a signal if they are not advanced in said order.

19. Means for feeding a plurality of control devices successively one at a time, certain of said devices being interrelated in groups, each group of interrelated devices comprising a master device and one or more subordinate devices, and the successive groups being assembled in a single series, means to identify each of the devices with the other devices of its group as it is fed, and means to stop the feeding operation if the identification shows that the devices are misgrouped.

20. The method of identifying with each other the individual elements of a group of perforated cards, each group including a master and a subordinate card of the type adapted to control a tabulator, comprising feeding the cards to be identified one at a time to a definite position and in said position comparing all cards of a single group with a single address printing member which is related to one of the cards of the group, and means for printing from the address printing member if all of the cards in the group agree with said member.

30 21. The combination with a comparison mechanism, wherein a series of master and subordinate control elements are successively fed one by one to an identifying position, of means to detect whether or not the subordinate elements are advanced immediately preceding the master element for such series, and means to effect a signal if they are not advanced in such order.

22. In combination a plurality of groups of control devices, printing devices supposedly related to all the members of respective groups, means to advance the printing devices one by one to a comparing position, means to advance all the members of a group to corresponding comparing positions with respect to the control members while the related printing device remains in the aforesaid comparing position.

23. In combination a plurality of groups of control devices, printing devices supposedly related to all the members of respective groups, means to advance the printing devices one by one to a comparing position, means to advance all the members of a group past the corresponding comparing positions with respect to the control members while the related printing device remains in the aforesaid comparing position, and indicia on the last control devices to be advanced for each group, a corresponding indicia on the related printing device, and means operated by the joint action of said indicia to move the said last control device and its related printing device from respective comparing positions.

24. In a printing mechanism, means to advance control cards step by step, a series of printing devices adapted to be fed step by step, indicia carried by the control cards, means cooperating with said indicia to initiate or cause the advance of the printing devices, and independent means cooperating with said indicia to cause or initiate a printing operation.

70 25. In a printing mechanism, means to advance control cards step by step, a series of printing devices adapted to be fed step by step, indicia carried by the control cards, means cooperating with said indicia to initiate or cause the advance of the printing devices, independent means coop-

erating with said indicia to cause two impressions to be made from each printing device.

26. In a printing mechanism, means to advance control cards step by step, means to advance printing devices step by step, indicia carried by the control cards, means cooperating with said indicia to cause two impressions to be made from each printing device, and means cooperating with the last-named means to render the card-feed mechanism and the device feeding mechanism ineffective during the second impression.

27. In a mechanism of the class described, the combination of a series of control members and a series of related printing devices, respective feeding means for said devices and members, indicia carried by related devices and members, detecting means to determine if the indicia favorably compare and means controlled thereby to cause two impressions to be made from printing devices which do favorably compare.

28. In a mechanism of the class described, the combination of a series of control members and a series of related address printing devices, respective feeding means for said devices and members, indicia carried by related devices and members, printing means and means operating to compare said indicia and to initiate the making of two successive impressions from the address printing devices which compare favorably with the control members.

30 29. In a mechanism of the class described, the combination of a series of control members and a series of related printing devices, respective feeding means for said devices and members, indicia carried by related devices and members, means to determine if the indicia favorably compare, said means operating to initiate a printing action from the compared printing device simultaneously on two work sheets.

35 30. In combination, a control member having a plurality of indicia positions, such that indicia in each position are capable of representing a plurality of different values, auxiliary means on the control members to determine which of such values in a given position represents other devices supposedly bearing indicia representing values equivalent to those of respective control members, and testing means to determine when the values represented by the indicia on a device and member correspond.

40 31. In combination, a control member having a plurality of indicia positions such that indicia in each position are capable of representing a plurality of different values, auxiliary means on the control members to determine which of such values in a given position represents other devices supposedly bearing indicia representing values equivalent to those of respective control members, testing means to determine when the values represented by the indicia on a device and member correspond, and means initiated by the corresponding indicia to effect a useful operation.

45 32. In combination a control member having a plurality of indicia positions, each position representing one or the other of two different values, correlated devices with indicia supposedly representing the same values as the values represented by the indexed control members, feeding means to advance the control members and devices in step with each other and means affected by the members and devices to perform a useful operation whenever the represented values mutually correspond.

50 33. In combination a plurality of address printing devices arranged in a series, means to feed

- and print from said printing devices, controlling mechanism for the feeding and printing mechanism, said controlling mechanism including a series of master and subordinate control cards and means included in said control mechanism to render the printing mechanism effective only when the master control cards arrive at a definite position relative to corresponding printing devices.
34. In a system for comparing control devices, comprising control devices having a plurality of possible indicia positions, electric relays for respective indicia positions, means whereby one of said relays will become energized consequent upon the presence of an index member in the respective indicia positions, means controlled by said relay to perform a useful function and means dependent upon indexes in corresponding position in another device to interrupt said circuit if the corresponding indexes are not present in the second device.
35. In a system for comparing control devices, comprising control devices having a plurality of possible indicia positions, electric relays for respective indicia positions, means whereby one of said relays will become energized consequent upon the presence of an index member in the respective indicia positions, means controlled by said relay to perform a useful function and means dependent upon indexes in corresponding position in another device to interrupt said circuit if the corresponding indexes are not present in the second device and to prevent said interruption if the corresponding indexes are present in said other devices.
36. In mechanism of the class described, the combination of means to feed a plurality of printing devices and control members step by step, a platen mechanism, certain only of the control members having an index to control said platen, and means set up by such index while a control member is in a selector position to control said platen, and means to retain said last-named means set up for several cycles of the control member feeding mechanism.
37. In mechanism of the class described, the combination of means to simultaneously feed a plurality of feeding devices and control members step by step, a platen mechanism, certain only of the control members having an index to control said platen, and means set up by such index while a control member is in a selector position to control said platen, means to retain said last named means set up for several cycles of the control member feeding mechanism, platen operating means, and means operated by the platen operating means to restore said selector means.
38. The combination of means to feed a control member to an identifying position, means to feed a printing device to an identifying position, means to compare said member and said device with each other in respective identifying positions, and means operated if they agreeably compare to advance the control member to a selecting position and bring a second control member into the identifying position, means carried by certain only of the control members and operated when such control members are in the identifying position to cause the printing device to advance to a selecting position, means to advance the printing device to printing position, selector means operated on the first-named member when in selecting position to determine whether or not the corresponding printing devices will be printed from when it arrives at the printing position.
39. The combination of means to feed a control member to an identifying position, means to feed a printing device to an identifying position, means to compare said member and said device with each other in respective identifying positions, and means operated if they agreeably compare to advance said control member to a selecting position and bring a second control member into the identifying position, means carried by certain only of the control means operated when such control members are in the identifying position to cause the printing device to advance to a selector position, selector means operated on the first-named member when in the selector position to determine whether or not the corresponding printing devices will be printed from when the next successive operation of the printing device feed brings the first-named printing device into printing position, and wherein one or more successive operations of the control member feed may take place before said printing device is in printing position.
40. The combination of means to feed a control member to an identifying position, means to feed a printing device to an identifying position, means to compare said member and said device with each other in respective identifying positions, and means operated if they agreeably compare to advance the control member to a selecting position and bring a second member into the identifying position, means carried by certain only of the control means operated when such control members are in the identifying position to cause the printing device to advance step by step to selector and printing positions, selector means operated on the first-named member when said member and the corresponding printing device are in their respective selector positions to determine whether or not the corresponding printing devices will be printed from when the next successive operation of the printing device feed brings the first-named printing device into printing position, and means whereby one or more successive operations of the control member feed may take place before said printing device is in printing position, and means actuated by the said operation of the selector means on the first-named control member to cause an impression to be made from the first-named printing member, even though the first-named control member has moved one or more steps in advance of the selector position.
41. In combination with an address printing machine having a series of address printing devices, means to intermittently feed said devices one at a time to an identifying position and then to a printing position, removable tabs carried by said printing devices, each tab adapted to represent either of two values, an embossed tab adapted to be positioned on said devices, the presence or absence of which determines which of said values said tabs represent, a series of supposedly corresponding cards to control the operation of the address printing mechanism, each card having a plurality of possible perforation locations, each location, when used alone, adapted to represent one definite value, one of said perforation locations acting when used with any other of said locations to change the value of such other locations, and electrical means responsive to the tabs and perforation to determine whether or not they represent the same values and ac-

cordingly control the operation of the addressing machine.

42. In combination with an address printing machine having a series of address printing devices, means to intermittently feed said devices one at a time to an identifying position and then to a printing position, removable tabs carried by said printing devices, each tab adapted to represent either of two values, a special removable tab adapted to be positioned on said devices, the presence or absence of which determines which of said values said other tabs represent, a series of supposedly corresponding cards to control the

operation of the address printing mechanism, each card having a plurality of possible index locations, each location, when used alone, adapted to represent one definite value, one of said index locations acting when used with any other of said locations to change the value of such other locations, and means responsive to the tabs on one printing device and the index on one of the cards to determine whether or not they represent the same values and accordingly control the operation of the addressing machine. 5 10

EMMETT C. HARTLEY.
